X-RAY TUBE

Application filed July 8, 1929. Serial No. 376,694.

The invention relates to the thermionic emission type of X-ray tubes and more particularly to improvements in tubes of the class forming the subject of our application Serial Number 299,650 filed August 15, 1928.

An object of the invention is to provide an X-ray tube adapted for medical and other purposes operable at comparatively low voltages.

Another object of the invention is to provide an X-ray tube whose operation is independent of small variations in the vacuum.

A further object of the invention is to provide an X-ray tube utilizing thermionic emission without using a separate source for heating the emitting surfaces.

A still further object of the invention is to provide an X-ray tube of the type described in which the main current through the tube is utilized for heating the thermion-emitting members.

Another object of the invention is to provide an X-ray tube of the class described in which the heat in the thermion-emitting surfaces is generated by induced currents or electronic bombardment, or both, the energy in each case being supplied by the main current through the tube.

A further object of the invention is to provide an X-ray tube of the class described having a thermally and electrically insulated pole placed in the path of the electrons in close proximity to the cathode, and arranged to serve as a thermionic emission member.

Another object of the invention is to provide an X-ray tube of the class described having a cup-shaped cathode, a thermionic emission member placed in the path of the electrons issued from the cathode, and a member supported at an inner point of the cathode cup and electrically connected to the latter to provide a part of the electric path, the adjacent parts of said last member and of the thermionic emission member being of the same general outline so as to insure the most efficient electronic pathway between the two members.

Another object of the invention is to provide an X-ray tube of the class described having a cup-shaped cathode and a helically

shaped member supported at the central inner point of the cup, said member carrying a part of the main tube current, being consequently heated by it, and thus giving rise to thermionic emission.

Another object of the invention is to provide an X-ray tube possessing current rectifying properties, the rectification being effected by thermionic members whose heat energy is derived from the main tube current.

Another object of the invention is to provide an X-ray tube of the class described having an auxiliary pole electrically connected to the target and placed in the electronic path in front of the target so as to raise the voltage gradient near the thermionic members.

Another object of the invention is to provide an internal construction of a thermionic type of X-ray tube which will make practical the use and operation of a tube of an unusually small cross-sectional area, whereby the X-ray generating portion of the tube may be readily inserted into cavities or orifices of the human body.

A further object of the invention is to provide an X-ray tube of the thermionic emission type having only two electrical conductors entering the tube.

A still further and an important object of the invention is to provide an X-ray tube of such external shape as to be adapted for intra-bodily X-ray therapy, fluoroscopic examinations, and radiographing parts of the human body, whereby only relatively small thickness of tissues need be penetrated by X-rays—thus enabling the operator to use soft X-rays with the consequent lessening of danger of pathogenic burning.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Fig. 1 is a longitudinal sectional view showing an embodiment of the X-ray tube of our invention.

5 Fig. 2 is a transverse sectional view taken on the line 2—2 in Fig. 1.

Fig. 3 is an enlarged plan view of a portion of the structure shown in Fig. 1.

10 Fig. 4 is a front view of the portion shown in Fig. 3.

As illustrated in the drawing, the X-ray tube 5 of our invention comprises a hollow body 6 preferably of constant circular section and defining an evacuated chamber. The 15 tube contains two electrodes—a cathode 7 and an anti-cathode 8—which latter provides a target 9. Electrical connection for the target and the cathode with a suitable source of power, such as the secondary of a transformer, 20 is established respectively through conductors 11 and 12 which, as here shown, also serve to support the electrodes in their proper alignment with respect to each other and the body. Both conductors 11 and 12 are electrically protected by tubular insulators 10 25 and 20 and extend longitudinally, preferably in parallel relation to each other, through the greater portion of the tube to support the cathode and the target near the free, or what 30 may be conveniently termed the X-ray emitting end 13 of the tube. To maintain the parallelism of the two conductors and to render the structure rigid a plurality of supports 30 made of suitable non-conducting material, such as glass, is interposed between 35 the conductors, the upper and lower ends of each support being preferably fused to insulators 20 and 10 respectively. In the present embodiment of our invention, as clearly 40 shown in Figure 1, the X-ray emitting member—the target—is placed adjacent the operative end 13 of the tube while the cathode is located further along the axis of the tube. This is extremely important since with such 45 arrangement X-rays may be most conveniently generated in parts of cavities of the human body difficult of access.

As is conventional, the target consists of a block 14 of tungsten or other suitable material, the operative surface 15 of which is arranged symmetrically with respect to the axis of the tube and defines with the latter an angle of about 45 degrees. The support for the block 14 is conveniently provided 50 through an angular extension 16 of the conductor 11, the adjacent surfaces of the block and the extension being in close metallic contact with each other. The cathode, as here shown, is substantially in the form of a hollow spherical shell or cup 17 whose axis coincides with the axis of the tube, and whose concave surface is arranged to focus the lines of force issuing from the cup at the central 55 point of the target. Extending towards the transformer end of the tube and forming an 60

integral part of the cathode is a hollow member 18 which is arranged to fit over the end 19 of the conductor 12, said end being in the form of a frustum of a cone with the narrower end of the frustum extending through 70 a perforation 21 in the central portion of the cathode cup and thus serving as the bottom 22 of the cup. It is clear from the above that a double function of supporting the cathode and serving as an electrical lead thereto is 75 conveniently exercised by a single conductor 12.

Preferably supported at the inner central point of the cathode cup 17 and extending outwardly therefrom along the axis of the 80 tube is a member 23 here shown in the form of a helical coil of tungsten wire, and having its axis common with that of the tube.

Facing the free end of the coil 23 and in fairly close proximity thereto is a neutral 85 pole 24 which is placed at the axis of the tube. In the present embodiment the pole 24 comprises a closed tungsten wire loop 25 having its axis at right angles to the axis of the tube and arranged to support a relatively 90 small target 26. The latter is conveniently made in the form of a thin circular disc of a diameter equal to that of the coil 23 and having its axis identical with the axis of the coil. The pole is suspended by a wire 27 which is 95 preferably fused into the free end of a non-conducting arm 28 of the insulator 20.

Positioned further along the axis of the tube, that is, between the neutral pole 24 and the target 9, is a relatively small auxiliary pole 29 which is attached to a wire 31 secured to an uninsulated part 32 of the conductor 11. The pole 29 is thus, as here shown, in electrical contact with the target and will at all times be at the same potential as the 105 latter.

The tube of my invention, like the Coolidge type, utilizes thermionic emission as the source of electrons, thus being practically independent of small variations of the vacuum, and, as in the latter type, by placing the emission members near the cathode and properly directing the electric field, self rectification is provided for. An important difference between the two types of tubes, however, lies in the fact that in the tube of our invention no separate source is necessary for heating the thermionic members. All the required energy for operating the tube is, as here shown, arranged to be supplied directly from the two terminals of the secondary of a transformer. This arrangement enables us to have only two current carrying members entering the tube instead of the three or more that are used in any other tube utilizing thermionic emission. Those skilled in the art can appreciate the greater facilities of insulation made possible by the reduction in the number of electrically independent conductors carried inside the tube. On 110 115 120 125

the other hand it is quite obvious that the lesser number of conductors permits the use of a tube of smaller diameter, since the latter is primarily controlled by the separation of 5 conductors at differing potentials. The importance of the size of X-ray tubes will be taken up later.

It being clear from the above that alternating voltage is impressed on the two conductors 11 and 12 connected to the target and cathode respectively, our next step will be to 10 explain how our invention has made it possible to utilize the power carried by only two conductors for both the heating of the thermionic members and for giving the target-bombarding electrons the necessary velocity 15 for production of X-rays.

We shall discuss at first the conditions existing during the brief but frequent intervals 20 when the cathode is negative and the target positive, and we shall term this polarity the normal polarity. When the tube is cold it should be started at a voltage higher than its 25 operative value. However, even the starting voltage need not be very high as the electronic path between the cathode and the target is greatly shortened by the introduction of the coil 23 and the auxiliary pole 29. Electrons supplied from the conductor 12 pass through 30 the coil 23 heating it thereby and are issued from the free end of the coil along the lines of force focused at the center of the target as determined by the conical electric field 35 defined by the cathode cup 17, this focusing being the most important function of the cup. Proceeding with enormous velocities towards the target, some of the electrons are abruptly stopped by the neutral pole 24 and give up 40 their kinetic energy in the form of heat—raising the temperature of the pole. The temperature of the latter is further raised by the eddy currents circulating in the loop 25 due to the fluctuations of the magnetic field 45 threading the loop, said fluctuations being clearly due to changes in the magnitude of the main tube current. The portion of the electronic stream which was not stopped by the neutral pole passes practically unobstructed by the very small auxiliary pole 29, 50 towards the anode. As the result of the impact upon the target, fairly hard rays will be emitted by the target corresponding to the high starting voltage, it being known that 55 the hardness of rays depends primarily upon the potential difference between the electrodes of the tube.

After a short interval, however, the coil 23 will become warm and the pole 24 very hot, 60 the former being heated by the current through it and the latter by electronic bombardment and eddy currents. Consequently both these members become sources of thermions. It is to be noted that while the coil 65 23 may lose part of its heat by conduction to

the member 12, the thermally insulated pole 24 will remain hot. The voltage across the tube may now be considerably reduced, no further necessity existing for high potentials 70 to tear electrons from the cold metal surfaces. The operator is thus free to choose the operative voltage to correspond to the hardness of X-rays required.

Due to the proximity of the neutral pole 24 and the free end of the coil 23, the electrons leaving either member and proceeding 75 towards the target will have to fall substantially through the total voltage across the tube. Thus all the electrons comprising the electronic stream will reach the target with 80 practically the same velocity, the slight difference in initial velocities of electrons from the pole and the coil respectively due to a difference in temperatures of the members 85 being entirely insignificant, since it is an established fact that the initial velocities of thermions are negligibly small in comparison with velocities of electrons fallen through thousands of volts.

Besides contributing to the homogeneity 90 of the electronic stream, the location of the pole and the coil at nearly the same point of the electric field represents an important factor in the self-rectifying function of the tube. Thus when the wave of the alternating voltage impressed on the tube causes the target to become temporarily negative and the cathode positive, the conditions for the electronic passage through the tube are radically 95 different from those prevailing with the normal polarity of the electrodes. The voltage reduced to its operative value is not sufficient to produce an electronic current of any appreciable magnitude from the comparatively cold target serving for the instant 100 as the negative terminal. It is amply high, however, to drive free thermions to a positive terminal which in this case is the cathode, or even tear off certain number of electrons 105 from a hot electrode such as the neutral pole 24. The neutral pole, however, cannot function as a source of electrons since it is electrically insulated, it being remembered that with the normal polarity the pole 24 was supplied with the electrons by the adjacent 110 warm coil 23. With the reversed polarity the pole 24 can lose but a limited number of electrons soon becoming highly positive and thus tending to attract rather than repel the negative electrons. It follows that even with an alternating voltage applied at the terminals of the tube, the current through the latter will be substantially unidirectional, 115 namely from the target to the cathode, or, stated in other words, electrons will always travel towards the target. What few electrons reach the cathode during the reversed polarity, will not be able to generate X-rays 120 for several reasons. First, the number of electrons will be small; second, their velocity 125 130

will be very low since electrons in their travel from the neutral pole to the cathode fall through but small difference of potential; and third, due to the substantially conically shaped field the electronic impacts will be distributed over the whole surface of the cup. It will of course be clear that while here we described the operation of the tube with alternating voltage impressed across the tube, partly rectified alternating voltage, or even direct current voltage, may be employed with at least equal advantage.

It will now be clear that the tube of our invention may be made of extremely small size without sacrificing the efficiency of its operation. The small size of X-ray tubes is an extremely important factor in medical work. For instance, a small tube may be inserted into cavities and orifices of the human body, thus making X-ray treatment, fluoroscopic examinations, and photographing, highly localized and precise. Moreover, as a direct consequence of the possibility of inserting a small tube into cavities of the human body, there arises the possibility of using the tube at a lower voltage than has heretofore been employed. Thus during a fluoroscopic examination of teeth a small tube can be placed in the mouth directly against the gums, while the screen may be arranged to be in contact with the cheek. Consequently X-rays have to penetrate but a small thickness of tissue and may accordingly be of low penetrability, that is, produced by a low voltage across the tube. It follows that using the tube of our invention the danger of pathogenic burning is greatly minimized, while the danger of electric shock to the operator or the patient is entirely obviated.

Of at least equal importance with the reduction in size of the tube as aforesaid, is the feature of arranging the X-ray emitting surface adjacent an extremity of the tube, which extremity is adapted for insertion in relatively small cavities of the human body or the like. The importance of this last feature cannot be over-estimated since the possibility of bringing the X-ray emitting surface into a close proximity to the tissue to be penetrated by the rays obviates the necessity for using hard X-rays and high voltages.

We claim:

1. In an X-ray tube, an envelope, a cathode, an anti-cathode, a coil electrically connected to the cathode and extending in the general direction of said anti-cathode, and a thermionic emission member comprising a relatively small target interposed between said coil and the anti-cathode to serve as a source of anti-cathode-bombarding electrons, the free end of said coil being adjacent said target and having approximately the same outline as the target.
2. In an X-ray tube a cathode, an envelope,

a target, a thermionic emission member electrically connected to the cathode to form a part of the electric path provided exclusively for the electrons designed to reach the target, another thermionic emission member electrically insulated from any source of power and interposed between said cathode and target, and an auxiliary pole placed in the path of electrons traveling towards the target and electrically connected to the latter.

70

75

3. In an X-ray tube, an envelope, a target, a cathode, and an auxiliary pole comprising a relatively small metallic member electrically connected to the target and located between the target and the cathode, thereby raising potential gradient throughout the tube without the necessity of changing the length of the electronic path from the cathode to the target, and thermionic emission members but one of which is electrically connected with the cathode and both of which are disposed between said pole and said cathode.

80

85

4. In an X-ray tube, an envelope, a cathode, an anti-cathode, a coil electrically connected to the cathode and extending in the general direction of said anti-cathode, a thermionic emission member interposed between said cathode and anti-cathode and electrically and thermally insulated from all operative parts of the tube, and a conductor connected to the cathode, a tubular insulator mounted to electrically protect said conductor and having a non-conducting arm, and a wire supporting said emission member and having an end fused into the free end of said arm.

90

95

5. In an X-ray tube, a cup shaped cathode, a metallic tubular extension on said cathode, a conductor engaged inside said extension and supporting said cathode, and a metallic coil electrically connected with and fastened directly to the portion of said conductor engaged in said extension.

105

6. In an X-ray tube, an envelope, a cathode, an anti-cathode, a coil electrically connected to the cathode and extending in the general direction of said anti-cathode, a pair of conductors for connecting the cathode and the anti-cathode respectively to a source of electric power, insulators to electrically protect said conductors, and a plurality of non-conducting supports interposed between said conductors to maintain the latter in a predetermined relation to each other and to the envelope.
